UNITED STATES PATENT OFFICE

2,291,658

STRIP TRIMMER

John Quirk Sherman, deceased, late of Dayton, Ohio, by Katherine M. Sherman, William C. Sherman, and Wellmore B. Turner, executors, all of Dayton, Ohio

Application August 3, 1940, Serial No. 350,546

10 Claims. (Cl. 164—38)

This invention pertains to paper trimming apparatus, and more particularly to a combined strip feeding and trimming device for removing the margins of continuous strips of record material as they are being advanced through a writing or imprinting machine or other strip treating apparatus.

Modern commercial stationary comprises continuous series-connected detachable forms arranged in superposed strips alternating with interleaved strips of carbon material. In order that such assembly of manifolding material may be uniformly advanced through a writing or imprinting machine, and registry and alignment be maintained between corresponding forms of each set and the material subsequently to be fed through a separating apparatus wherein the superposed record strips and interleaved carbon strips are separated from each other and perhaps thereafter fed through a form bursting mechanism by which the strips are transversely severed into individual sheets, the strips of series-connected forms are marginally punched to provide longitudinally spaced holes for engagement of pin type feeding devices embodied in the respective machines. Other styles of feeding mechanism may be employed which may necessitate embossed areas or projecting tongues along the strip margins or which may mar or mark the margins of the strips. The marginally punched holes or other marginal configurations of the strips are primarily for feeding purposes, and when they have performed such function for the last time during either the writing, imprinting, separating or severing operations, their usefulness is ended and they may be dispensed with entirely.

To some persons such marginal configurations may appear unsightly. In other instances it may be desirable to somewhat reduce the size of the ultimate sheets for convenience of filing or handling. In either event, it is desirable to remove such marginal feeding areas when their purpose has been served and they are not longer necessary. In the present instance there is contemplated a combined strip feeding and trimming unit wherein the margin of the strip is progressively removed in unison with its advancement, the feeding and trimming operations being synchronized with each other.

The object of the invention is to simplify the construction as well as the means and mode of operation of strip feeding and trimming devices, whereby they may not only be economically manufactured, but will be efficient in use, uni-

form in operation, automatic in action, have but few operating parts and be unlikely to get out of repair.

A further object of the invention is to provide a combined strip feeding and trimming unit wherein the parts thereof will cooperate with each other to progressively trim a marginally punched strip coincident with its advancement.

A further object of the invention is to provide 10 a unit of compact form capable of being readily installed in existing strip treating apparatus or which may be conveniently incorporated in new mechanisms at the time of their construction.

A further object of the invention is to provide 15 an improved form of cutter mounting, and to improve the cooperative relation between the feed member and the cutter element.

A further object of the invention is to provide 20 a strip feeding and trimming unit having the advantageous structural features and inherent meritorious characteristics herein mentioned.

With the above primary and other incidental objects in view as will more fully appear in the specification, the invention intended to be protected by Letters Patent consists of the features 25 of construction, the parts and combinations thereof, and the mode of operation, or their equivalents, as hereinafter described or illustrated in the accompanying drawing.

In the accompanying drawing, wherein is illustrated the preferred, but obviously not necessarily the only form of embodiment of the invention, Fig. 1 is a perspective view of a combined strip feeding and trimming unit embodying the present invention. Fig. 2 is a side elevation thereof. Fig. 3 is a similar view from the opposite side of the unit. Fig. 4 is a top plan view thereof. Fig. 5 is a side view showing the strip guide finger and cutter in retracted position to facilitate the initial engagement of the strip material with the feeding device. Fig. 6 is a perspective view of a packet of marginally punched strip material showing the partial severance of marginal areas thereof as by the present trimming device. Fig. 7 illustrates a modification. Fig. 8 illustrates an addition whereby vibratory motion is transmitted to the knife.

Like parts are indicated by similar characters of reference throughout the several views. 50 While the unit illustrated is especially adapted for simultaneously feeding and trimming marginally punched stationery, to remove therefrom its punched marginal area it is to be understood that other feeding means than that illustrated are contemplated wherein the strip margins may

have other feeding configurations than those disclosed, such as embossed areas, struck-up tongues or other formations, or wherein the strip is fed by frictional contact or by marginal engagement of other types of feeding devices.

The present unit may be employed to sever the strip on a longitudinal line by cutting action in the event that the division line has not been previously weakened, or in the latter event a relatively dull tool may be used for breaking the strip on such pre-weakened line.

Referring to the drawing, 1 is a rotary shaft upon which either a single or a pair of strip feeding and trimming units are mounted for unison rotation and for axial adjustment. Usually the stationery is marginally punched at opposite edges, both of which are to be removed. Hence the necessity for plural trimmers. However, for some purposes the strip material is fed by a single succession of feeding holes, in which case but one such combined unit may be necessary.

The present unit includes a pin wheel 2 having thereon a plurality of radial feeding pins 3 for progressive engagement in marginal holes 4 in the superposed strips 5 of record material for feeding and aligning the strips as they approach writing, imprinting or other operative positions, to maintain registry of superposed data imprinted thereon.

The particular pin wheel illustrated is of the type having reciprocatory feeding pins which are successively projected into engaging relation in the holes 4 of the strips and retracted therefrom as the wheel 2 is rotated. Such automatic operation of the feeding pins is shown and described in Reissue Patent No. 20,888, and forms no part, per se, of the present invention. A conventional form of pin wheel having relatively fixed pins may be used with equal facility and results.

The pin wheel 2 is extended laterally inwardly of the plane of the feeding pins 3 forming a cylindrical face 6 having therein a peripheral groove 7. Mounted upon a shaft 8 in parallel relatively spaced relation with the pin wheel is an arm 9 capable of oscillatory movement, toward and from the pin wheel. The arm 9 is provided with a hub 10 journaled on a trunnion sleeve 11 mounted on the shaft 8 and adapted to be fixedly secured thereto in various positions of axial adjustment. The arm hub 10 is secured on the sleeve 11 against axial movement by a collar 12, which is transfixed by a set screw 13 threaded in the trunnion sleeve 11 and engaging the shaft 8 to lock the sleeve thereto. The arm 9 and hub 10 are secured in adjusted rotative position about the bearing sleeve by a set screw 14 threaded in the hub 10 and engageable with the trunnion sleeve 11. Located beside the arm 9 is a slotted arcuate paper guide or hold-down member 15, one end of which is formed into an eye 16 enclosing the shaft 8 and the free end of which is formed with opposite spaced upstanding ears 17 connected transversely to the extremity of the arm 9 by a stud 18. The construction is such that the slotted guide finger 15 is movable to and fro about the shaft 8 in unison with the arm 9 and is held in its adjusted position by locking the arm. The assembly is further adjustable axially of the shaft 8 and held in adjusted position by the set screw 13. In its operative, depressed position, the arcuate guide finger 15 extends in concentric spaced relation with the pin wheel 2 in such relation that the

feeding pins 3 extend through the holes 4 of the superposed strips 5 and thence through the slot 15' of the guide finger 15. Thus the slotted finger retains the strips 5 in operative engagement with the feeding pins, preventing their accidental disengagement therefrom, but without imposing any frictional resistance to advancement of the strips by the pin wheel.

Carried also by the arm 9 and extending in transverse elevated relation with the slotted guide finger 15 is stud 19 of relatively large diameter, which is transversely slotted adjacent its extremity to adjustably receive a cutting blade 21 which may be secured in adjusted position by a set screw 22 in the end of the mounting stud 19.

The cutter blade is disposed in the plane of the peripheral groove 7 in the face 6 of the pin wheel, into which the lower end of the cutter blade is projected. The cutter blade 21 is preferably, although not necessarily, inclined to the direction of travel of the strips. The upper end of the cutter, above the mounting stud 19, is enclosed in a channel shaped sheath 23 affixed to the mounting stud.

Upon elevation of the guide finger 15 to enable initial engagement of the strips to be fed with the feeding pins, the cutter blade is elevated in unison therewith as is shown in Fig. 5, after which the oscillatory arm and with it the guide finger 15 and cutter blade 21 are returned to operative positions as illustrated in Figs. 1, 2 and 3.

The strips 5 are progressively advanced by engagement of successive pins 3 in the holes 4 as the pin wheel is rotated. The strips are thus drawn against and past the cutter blade 21, which severs the strips upon a longitudinal line parallel with the lateral edge of the strips at the inner side of the succession of feed holes 4, thus removing from the strips narrow continuous marginal areas 24 as is shown in Fig. 6. In Fig. 7 there is shown a modification wherein in lieu of mounting the cutter blade 21 upon the arm 9, the cutter is mounted independently thereof upon an arm 25 carried by a shaft 26 and held in adjusted position thereon by a set screw 27. The knife 21 projects from its supporting arm 23 across the path of the strips fed by the pin wheel. In this embodiment the strip path is intermediate two spaced guide plates 28 having therein registering openings 29 through which the knife 21 extends. Obviously, if the strips have been pre-weakened along the line of severance, the member 21 need not be sharpened as a knife, but may have a relatively dull edge which, engaging the strips coincident with the weakened severance lines, will serve to break the strips therealong without actual cutting action.

When severing strips of material of certain character, it may be found that the material resists a straight thrust cut, but will yield to a draw cut, or that lint may collect upon and clog the edge of the cutter. In either event, it is found desirable to transmit to the knife a jogging motion, which will clear the knife of lint, and will facilitate the cutting of resistant strip material.

To this end there is shown in Fig. 8 an addition to the structure before described wherein there is attached to the side of the pin wheel 2 a notched or serrated ring 30 engaged by a roller 31 carried on the end of the slotted paper guide or hold-down arm 15. As the pin wheel rotates, a vibratory motion incident to the engagement of the roller 31 with the toothed ring 30 transmits

a vibratory motion to the slotted arm 15 and thence to the cutter blade. This imparts a slight to and fro draw cut of the knife against the advancing strip, which facilitates its division and detaches any adhering particles.

The subject matter of the present application is broadly disclosed, but not particularly claimed, in copending application Serial No. 279,341, which is a division of an earlier application Serial No. 116,552, filed December 18, 1936, now matured into Letters Patent No. 2,172,414, and copending application Serial No. 294,199, which is a division of an earlier application Serial No. 115,804, filed December 14, 1936, and now matured into Letters Patent No. 2,177,675, and in copending application Serial No. 277,484, which is a continuation in part of an earlier application Serial No. 157,706, filed August 6, 1937, now matured into Letters Patent No. 2,160,916.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described the invention, what is claimed is:

1. In a strip trimming device, a rotary pin wheel, the pins of which have progressive engagement in a succession of longitudinally spaced holes in a strip of material for advancing the strip past a severing position, the pin wheel having therein a peripheral groove, a cutter knife disposed in the plane of said groove with its terminal end projecting thereinto, an adjustable mounting upon which the knife is carried for movement toward and from the pin wheel, and means for transmitting a vibratory motion to the knife mounting to effect a jogging draw cut action of the knife upon a strip advanced by rotation of the pin wheel to remove from the strip a marginal portion containing said succession of longitudinally spaced holes.

2. In a strip trimming device, a rotary pin wheel, the pins of which have progressive engagement in a succession of longitudinally spaced holes in a strip of material for advancing the strip past a severing position, a peripheral groove in the pin wheel in parallel offset relation with the feeding pins, an elongated cutter blade against which the strip is advanced by the pin wheel, the extremity of which extends into the peripheral groove, the cutter being operative to progressively remove from the advancing strip a marginal portion thereof containing the succession of longitudinally spaced holes.

3. In a strip trimming device, a pin type strip feeding device, the pins of which have progressive engagement in a succession of longitudinally spaced holes in a continuous strip of material, a

groove in the feeding device in parallel offset re-

lation with the feeding pins, a severing device disposed in the path of the advancing strip coincident with the groove in the feeding device relative to which the strip is advanced by the pin type strip feeding device, and means for transmitting vibratory motion to the severing device in unison with the advancement of the strip, said device being operative to remove from the strip a marginal portion thereof containing the succession of longitudinally spaced holes.

4. In a strip trimming device, a pin type strip feeding device, the pins of which have progressive engagement in a succession of longitudinally spaced holes in a continuous strip of material having a preweakened division line in parallel offset relation with the succession of longitudinally spaced holes, a severing device disposed in the path of travel of the strip coincident with the preweakened line thereof, relative to which the strip is advanced by the pin type feeding device, and means for transmitting vibratory motion to the severing device in unison with the advancement of the strip, said device being operative to remove from the strip along said weakened line a marginal portion thereof containing said longitudinally spaced holes.

5. In a strip trimming apparatus, a strip feeding device having progressive engagement with a marginal portion of a continuous strip of material for advancing the strip past a severing position at which a marginal area thereof engaged by the feeding device is progressively removed from the strip, a severing device positioned in the path of advancement of the strip, and offset out of alignment with the strip feeding device, a swinging arm on which the severing device is mounted for swinging adjustment toward and from intersecting relation with the plane of the strip, and mounting means by which the severing device is adjustable on said arm, and means for securing the arm and the severing device in positions of adjustment.

6. In a strip trimming device, a pin type strip feeding device, the pins of which have progressive engagement in a succession of longitudinally spaced holes in a continuous strip of material, a severing device disposed in the path of the advancing strip relative to which the strip is advanced by the pin type strip feeding device, and means for transmitting vibratory motion to the severing device in unison with the advancement of the strip, said device being operative to remove from the strip a marginal portion thereof containing the succession of longitudinally spaced holes.

7. In a strip trimming device, a rotary pin wheel, in arm pivotally mounted for movement relative to the pin wheel the axis of which is in parallel offset relation to the axis of the pin wheel, an elongated severing device adjustably secured to the arm and operatively extending within the periphery of the pin wheel, the construction and arrangement being such that by adjustment of the arm the severing device is brought into and out of co-operative relation with the pin wheel.

8. In a strip severing device, a rotary pin wheel unit, an elongated severing element which when in operative position intersects a plane tangent to the pin wheel unit, a guide element for maintaining the strip to be severed in proximate relation with the pin wheel, and a pivotally mounted arm upon which the guide and severing elements are supported, the axis of oscillation of said arm being in parallel offset relation to that of the pin wheel unit.

9. In a strip severing device, a rotary pin wheel unit, an arm adjustably mounted for oscillatory and longitudinal movement relative to the pin wheel the axis of which is in parallel offset relation to the axis of the pin wheel, a guide 5 for maintaining the strip to be severed in proximate relation with the pin wheel carried thereby, a second arm mounted for oscillatory and longitudinal movement relative to the pin wheel the axis of which is in parallel spaced relation to the 10 axis of the first arm, and an elongated severing element supported by said second arm in intersecting relation to a plane tangent to the pin wheel unit.

10. In a strip trimming device, a rotary pin 15 wheel, an arm pivotally mounted for movement relative to the pin wheel the axis of which is in

parallel offset relation to the axis of the pin wheel, an elongated severing element adjustably secured to the arm and operatively extending in overlapping relation with the periphery of the pin wheel, a paper guide for operatively maintaining the strip to be severed in proximate relation to the pin wheel the construction and arrangement being such that by adjustment of the arm the severing element and the paper guide are movable into and out of cooperative relation with the pin wheel.
